Primary Examiner — Ramzi S Almatrahi(74) *Attorney, Agent, or Firm* — David W. Carstens; James D. Tuck; Carstens & Cahoon, LLP(57) **CLAIM**

The ornamental design for a camera, as shown and described.

DESCRIPTION

FIG. 1 is a front view of a camera according to our new design;

FIG. 2 is a back view of the camera shown in FIG. 1; FIG. 3 is a left view of the camera shown in FIG. 1; FIG. 4 is a right view of the camera shown in FIG. 1; FIG. 5 is a top view of the camera shown in FIG. 1; FIG. 6 is a bottom view of the camera shown in FIG. 1; and, FIG. 7 is a perspective view of the camera shown in FIG. 1. The broken lines depict portions of the camera in which the design is embodied that form no part of the claimed design.
